1. A tie-plate having parallel continuous ribs extending nearly across plate and between which a rail may be placed and secured by bending down said ribs over the base-flanges of said rail, to form clamping-jaws. 5 down said jaws over the base-flanges of said rails, said plate also having a slot and arched member adapted respectively to receive and hold the head of a tie-rod, in combination with said tie-rod. 45
2. A tie-plate having ribs thereon approximately perpendicular to said plate, and extending from alternate edges thereof, and each terminating short of the edge opposite that from which it starts, said ribs being of a height sufficiently greater than the base-flanges of a rail to allow them to be bent over and to clamp said flanges. 10 7. In a railroad-track securer, tie-plates having jaws thereon adapted to grip the base-flanges of a rail, and also having slots and arched members adapted respectively to receive and hold the heads of tie-rods, in combination with tie-rods, means for adjusting 55 said tie-rods, and means for holding said rods in adjustment. 50
3. A tie-plate having spike-holes disposed diagonally and spaced transversely a distance, to leave a rail-seat therebetween, the said holes being adjacent to opposite edges of the plate, the said plate also having bendable ribs rising from the upper surface a height sufficient to be bent over onto the rail-flanges, the said ribs extending from opposite edges to points adjacent to the mentioned spike-holes, and lying in line with said holes. 15 8. A tie-rod having a head at each end, in combination with tie-plates having slots for receiving said heads and openings to receive the tie-rod, said openings leading out through the under face of the plate and to said slots. 60
4. A tie-plate adapted to receive near each of its four corners spikes for securing said plate, adapted also to receive one spike at each end of the tie-plate adjacent to the rail but on opposite sides thereof, said spikes being adapted to grip the base-flanges of the rail, said tie-plate having also ribs on each side of the rail running parallel thereto and extending clear across the surface of the tie-plate except for spaces diagonally disposed at opposite edges of said tie-plate. 30 9. In a railroad-track securer, tie-plates adapted to receive near each of their four corners spikes for securing said plate, and adapted also to receive one spike at opposite edges of the plate adjacent to and on opposite sides of the rail near enough thereto to grip the base-flanges of said rail, said tie-plates having also ribs on each side of the rail parallel thereto, and of a height sufficiently greater than the base-flanges thereof to allow them to be bent over and clamp said flanges, extending clear across said tie-plate except for a space at alternate ends of said plate, said tie-plates also having each a tie-slot and arched member adapted respectively to receive and hold the head of a tie-rod, in combination with tie-rod, means for adjusting 75 70 said tie-rod, and a means for securing the rods so adjusted. 75
5. A rail-securer consisting of a plate having ribs or jaws thereon between which the rails may be placed and secured by bending down said jaws over the base-flanges of said rail, said plate also having a slot and arched member adapted respectively to receive and hold the head of a tie-rod. 35 5. A rail-securer consisting of a plate having ribs or jaws thereon between which the rails may be placed and secured by bending down said jaws over the base-flanges of said rail, said plate also having a slot and arched member adapted respectively to receive and hold the head of a tie-rod, in combination with tie-rod, means for adjusting said tie-rod, and a means for securing the rods so adjusted. 80
6. A rail-securer consisting of a plate having ribs or jaws thereon between which the rails may be placed and secured by bending
